ATTACHMENT FOR COPYHOLDERS

Bonnie E. Van Alstyne, San Francisco, Calif.

Application August 13, 1934, Serial No. 739,683

17 Claims. (Cl. 120—29)

My invention relates to improvements in attachments for copy holders, and it consists of the combinations, constructions and arrangements hereinafter described and claimed.

An object of my invention is to provide a copy holder which is an improvement over the forms shown in my three Patents Nos. 1,903,523, issued April 11, 1933, No. 1,908,874 issued May 16, 1933, and No. 1,950,706 issued March 13, 1934, and also is an improvement over the five pending applications, Serial No. 676,381, filed June 17, 1933, allowed June 19, 1934, Serial No. 704,998, filed January 2, 1934, Serial No. 717,245 filed March 24, 1934, Serial No. 733,636, filed June 3, 1934, and Serial No. 737,629 filed July 30, 1934.

I make use of a standard copy holder which is designed to be positioned in back of a typewriter, and which has a stationary part and a movable part. A lever lifts the movable part step by step as the lever is actuated, and this causes the copy to be raised with respect to a line indicator as the typist desires. After the movable part has lifted the page being copied to a point where the line indicator is positioned at the lowermost line on the page, then the movable part can be lowered and the page turned and the same operation can be repeated. The copy holder forms no part of my present invention except that I make use of it with my attachment so that the copy holder is adapted to support a sidewise opening book, where without the attachment, it could only support a sheet of paper or a note book. The attachment is removably secured to the copy holder, and when in use it is secured to the movable portion of the copy holder, and when not in use it may be secured to the stationary portion of the copy holder.

A further object of my invention is to provide a device of the type described in which novel mechanism is used for holding the line indicator on the attachment in a fixed position while moving the attachment and the book carried thereby upwardly step by step so that the line indicator will progressively indicate successive lines on the page.

A further object of my invention is to provide an attachment having a line indicator that is adjustable laterally for accommodating itself to books of various sizes.

Still a further object of the invention is to provide an attachment which may be inclined at the desired angle with respect to the movable portion of the copy holder so that the operator may bring the book into a position directly above the

typewriter, thus materially aiding the operator in reading the page being copied.

Other objects and advantages will appear in the following specification, and the novel features of the device will be particularly pointed out in the appended claims.

My invention is illustrated in the accompanying drawings forming a part of this application, in which

Figure 1 is a perspective view of a typewriter 10 and a copy holder showing the attachment operatively secured thereto;

Figure 2 is a perspective view of the rear of a copy holder showing the attachment mounted in inoperative position;

Figure 3 is a fragmentary front view of the attachment and copy holder, portions of both being broken away for the purpose of illustrating the device on a large scale;

Figure 4 is a vertical section through the book 20 holding device and line indicator;

Figure 5 is a front elevation of the attachment without the book holding device;

Figure 6 is a side view of Figure 5;

Figure 7 is a bottom plan view of Figure 5;

Figure 8 is a section along line 8—8 of Figure 5;

Figure 9 is a section along the line 9—9 of Figure 3;

Figure 10 is a section through another portion 30 of the device; and

Figure 11 is a rear elevation of the catch used for holding the folding book shelf in inoperative position.

In carrying out my invention I make use of a standard copy holder indicated generally at 1, and in Figure 1 I show this copy holder in operative position with respect to a typewriter indicated generally at 2. Although the copy holder forms no part of my invention, I will briefly describe it in order to show how my attachment cooperates with the copy holder in order to adapt it to indicate lines to be copied from a sidewise opening book. The copy holder comprises a fixed member 3 and a movable member 4. The movable member is designed to be lifted vertically step by step a predetermined distance at each step, and this is accomplished by means of a lever 5 which actuates a lifting mechanism not shown. A line indicator 6 for the copy holder is pivotally carried by a frame 7 which is pivoted at 8 to the stationary member 3 of the copy holder. A spring pressed rod 9 is pivoted at 10 to the top of the movable member 4, and the purpose of this rod is to hold

sheets of paper or a note book from which copying is to be done.

In order to adapt the device to support a side-wise opening book I provide an attachment one part of which is shown in detail in Figures 5 to 7 inclusive. The attachment comprises two hook-shaped arms 11 and 12 that are designed to be removably secured to the rod 9 when the attachment is to be used. When the attachment is not in use the hook-shaped arms 11 and 12 may be secured to the frame 7 as shown in Figure 2, so as to dispose the attachment at the rear of the copy holder. In the first instance the attachment is carried by the movable member 4, and is raised when the member 4 is raised, while in the second instance the attachment is carried by the stationary member 3 and remains in the same position even though the member 4 may be raised and lowered.

At the lower ends of the arms 11 and 12 I dispose a book-supporting back 13, and a swingable book-supporting shelf 14 is hinged to the back 13 at 15. Figure 7 clearly illustrates how the lower ends of the arms 11 and 12 are bent for providing stops 16 and 17, and these stops are inclined at an acute angle with respect to the arms 11 and 12 so that the shelf 14 when in open position will also extend at an acute angle with respect to the back 13.

I provide means for swinging the lower end of the attachment away from the member 4 at an angle so that the typist can incline the book at the desired angle. This is accomplished by sleeves 18 and 19 that are slidable on the arms 11 and 12, and that are connected by a cross piece 20. Each sleeve 18 and 19 carries a foot 21' that has a rounded end 22', see Figure 6, for bearing against the front surface of the member 4. It is obvious that as the sleeves 18 and 19 are moved up toward the top of the arms 11 and 12, the feet 21' will cause the attachment to swing away from the member 4 at a greater angle. In this simple way not only the desired angle of the attachment can be obtained, but also the side-wise opening book itself may be moved toward the typist where the printing on the book can be more readily seen. The cross piece 20 performs the additional function of acting as an auxiliary back supporting member for the book and co-operates with the back 13 in this respect.

I provide means for holding the book in open position on the back 13, and this means also carries the line indicator for the book. In Figures 3 and 4 I show a bar 21 pivoted to the top of the member 4 at 22, see Figures 1 and 2, and I further show a second bar 23 pivoted to the shelf 14 at 25, see Figure 7. Figure 4 shows the bar 21 as being slotted at 26, and as having serrations 27 in its upper surface. Figure 7 shows the bar 23 being provided with a plurality of slots 28, and these slots extend at a slight angle for a purpose to be hereinafter described.

The book holder comprises a vertical rod 29 and having a T-shaped top 30. This top is turned so as to be in alignment with the slot 26 when the top is passed through the slot, and then the rod 29 is rotated on its axis through 90° so that the sides 31 of the top will straddle the sides of the bar 21. Figure 3 clearly shows this arrangement, and also shows the vertical rod 29 extending through the slot 26. The under surface of the top 30 is inclined as at 32, see Figure 4, for the purpose of providing two teeth that will enter the various serrations 27. These teeth permit the rod 29 to be moved toward the member 4 but

prevent movement in the opposite direction unless the top is lifted so as to free the serrations.

The lower end of the rod 29 is provided with a hand grip 33 and the portion of the rod disposed adjacent to the hand grip is removably receivable in any one of the slots 28 in the bar 23. It is obvious that when the book holder is used that the bars 21 and 23 are swung from the positions shown in Figure 2 into positions where they will extend forwardly from the copy holder and from the shelf 14.

The bottom edges of the leaves of a book 34 shown in Figure 1 are held in open position by an angle-shaped member 35, see Figure 3, that is rigidly secured to the rod 29 by means of a sleeve 36. The bottom side 37 of the angle member 35 is positioned so as to be disposed slightly above the shelf 14 when the latter is in open position.

The top edges of the sidewise opening book 34 are likewise held in open position by a second angle member 38 that is slidably mounted on the rod 29 by means of a sleeve 39. It will be noted that the bottom side 37 of the member 35 and the top side 40 of the member 38 are provided with recesses 41 and 42, see Figure 4, for the purpose of receiving the book hinge. The top member 38 may be quickly adjusted to accommodate books of different sizes.

I also show means for indicating the line being copied, and reference to Figures 3 and 4 will show that I provide a sleeve 43 that is slidable on the rod 29 but frictionally engages with the rod so as to tend to remain in the position into which it is moved. A second sleeve 44 is secured to the sleeve 43 and is disposed at right angles thereto so as to slidably carry the line indicator 45. The line indicator 45 is adjustable laterally in the sleeve 44 so as to accommodate itself to books of different widths.

I provide novel and simple means for holding the line indicator 45 against movement, or in the same position, while the member 4 and the attachment carrying the book are raised step by step. In Figure 3 a cord 46 is secured to a bracket 47 which in turn is attached to the bottom of the stationary member 3 of the copy holder. The upper end of the cord is inserted in a V shaped clamp 48, see Figure 9, and the clamp in turn has its side 49 soldered or otherwise secured to a knob 50. The other side 51 of the clamp 48 is designed to be moved into gripping position on the cord 46 when a set screw 52 is tightened. When the set screw 52 is loosened the cord 46 may be removed from the clamp. The clamp can be secured to the cord at any desired position, and then held in this position by the set screw 52. It will now be seen that as the member 4 and the book attachment are raised the cord or string 46 will hold the line indicator 45 from raising, and this will cause the line indicator to slide on the rod 29 and to indicate the line being copied, as the rod is moved upwardly with the member 4.

I further show novel means for supporting either cover of the book in spaced relation with respect to the arms 11 and 12. For example, in Figure 1 I show the greater portion of the book 34 disposed on the left hand side of the rod 29. In order to bring the right hand page into a position to be parallel with the surface of the left hand page it is necessary to move the right hand cover 53 of the book away from the arm 12. This is done by a leaf spring 54 which is attached to the bottom of the arm 12 at 55, and which is slidable in a sleeve 56, the latter

being carried by the arm 12. A hand grip 57 is secured to the top of the spring, see Figure 5, and this grip has a pin 58, see Figure 6, that enters any one of a desired number of openings 59 provided in the arms 11 and 12. The hand grip may be moved downwardly and secured in place by the pin 58, and this will cause the portion of the spring below the sleeve 56 to buckle as shown in Figure 1 and to support the book cover 53. A similar spring is provided on the arm 11 and corresponding reference numerals will be given. This spring is used when the greater portion of the book is disposed on the right hand side of the rod 29 rather than on the left.

In Figures 2 and 11 I show a catch 60 pivoted to the arm 11 at 61, and this catch has a U-shaped portion 62 for engaging with the shelf 14 when the latter is swung into closed position. The catch 60 holds the shelf in closed position.

In Figure 10 I show a novel manner of pivotally securing the bar 23 to the shelf 14. The shelf is countersunk as at 63, and the bar 23 has a countersunk recess 64 for receiving the countersunk portion 63 of the shelf. A screw 65 is passed through the line of openings in the shelf and in the bar and a nut 66 is threaded on the screw and bears against a spring washer 67 which in turn bears against the bar 23. The countersinking of the bar 23 at 64 does away with the necessity of providing a washer between the bar 23 and the shelf 14.

From the foregoing description of the various parts of the device the operation thereof may be readily understood.

When the device is used the hook-shaped arms 11 and 12 are attached to the rod 9, and then the sleeves 18 and 19 are moved on the arms 11 and 12 so as to extend the attachment at the desired angle with respect to the member 4. The book 34 is now placed in position and the book holder is secured to the bars 21 and 23. The string 46 is now attached to the line indicator 45 after the indicator has been moved into the desired position. If the leaf springs 54 are needed to support either cover on the book, they can be adjusted in the manner already indicated.

The device is now ready for use and the book will be raised line by line as the lever 5 is actuated. The indicator 45 will be held in the same position and will therefore indicate each successive line as the work is copied.

When the device is not in use the hooks 11 and 12 are removed from the rod 9, and are attached to the frame 7 so that the attachment is positioned in back of the copy holder. The shelf 14 is swung into closed position and the catch 60 holds the shelf in this position. The bars 21 and 23 are also swung into inoperative position. It is obvious that if the operator does not wish to dispose the attachment on the back of the copy holder when the attachment is not in use, this need not be done.

In Figure 3 the indicator 45 is shown moved slightly to the right in the sleeve 44. It is possible to move the indicator 45 either to the left or to the right, and in this way accommodate books of different widths. The purpose of inclining the slots 28 is to cause the rod 29 to be forced toward the closed end of the slot when the rod is urged outwardly by the pressure of the book. Figure 1 shows how the book is held in open position, and it will be noted that the book will be forced against the member 35, and this in turn will tend to move the rod 29 away from the member 4. It is this movement that will

cause the rod 29 to come to rest at the closed end of the slot 28 because the slots are inclined in the manner shown in Figure 7.

The shelf 14 has a recess 24 centrally disposed therein for receiving the rod 29.

I claim:

1. The combination with a copy holder having a fixed member and a movable member, and means for lifting the movable member vertically step by step, of an attachment removably secured to the movable member, means carried by the attachment for supporting a sidewise opening book in open position, and a line indicator carried by said means and being adjustably anchored to the fixed member for causing the line indicator to progressively indicate successive lines on the book while the movable member is lifted vertically.

2. The combination with a copy holder having a fixed member and a movable member, and means for lifting the movable member vertically step by step, of an attachment removably secured to the movable member, means carried by the attachment for supporting a sidewise opening book in open position, and a line indicator carried by said means and being adjustably anchored to the fixed member for causing the line indicator to progressively indicate successive lines on the book while the movable member is lifted vertically, and means carried by the attachment for moving either cover of the book toward the line indicator for causing the two exposed pages of the book to lie in the same plane, and to be disposed in back of the line indicator.

3. The combination with a copy holder having a fixed member and a movable member, and means for lifting the movable member vertically step by step, of an attachment removably secured to the movable member and having a book supporting shelf, a bar pivoted to the top of the movable member, a second bar pivoted to the shelf, a rod removably secured to the two bars, and designed to be placed in front of a sidewise opened book, and a line indicator slidably on the rod and being anchored to the fixed member for holding the indicator in the same position as the movable member is lifted.

4. The combination with a copy holder having a fixed member and a movable member, and means for lifting the movable member vertically, of an attachment pivotally secured to the movable member, a book supporting shelf and back carried by the attachment, means for swinging the attachment into the desired angular position with respect to the movable member, means for holding a sidewise opening book in open position, the book being supported by the shelf, a line indicator slidably carried by the book holding means, and an adjustable cord extending from the indicator to the fixed member for causing the indicator to move with respect to the book when the movable member is raised.

5. The combination with a copy holder having a fixed member and a movable member, and manually controlled means for stepwise lifting the movable member, of an attachment hingedly secured to the movable member and having a book supporting shelf, leaf springs adjustably carried by the attachment for holding the covers of a book in the desired positions, means for holding the book in open position, and including a line indicator slidably carried thereby, a cord attached to the fixed member and having its free end adjustably connected to the line indicator.

6. An attachment for a copy holder comprising

- ing two hook-shaped arms, a back for supporting a book, and a hinged shelf for supporting the bottom of the same book, and a hook for holding the hinged shelf in closed position.
5. 7. An attachment for a copy holder which will adapt the copy holder to support a sidewise opening book and comprising two hook shaped arms carrying a book supporting back, a shelf hinged to the lower edge of the back, said arms having 10 portions bent adjacent to the shelf for constituting stops that will support the shelf in open position, and a catch for holding the shelf in closed position.
8. An attachment for a copy holder which will 15 adapt the copy holder to support a sidewise opening book and comprising two hook shaped arms carrying a book supporting back, a shelf hinged to the lower edge of the back, said arms having portions bent adjacent to the shelf for constituting 20 stops that will support the shelf in open position, and a catch for holding the shelf in closed position, leaf springs carried by the arms, and means carried by the leaf springs and the arms for holding the leaf springs in an arcuate shape, the leaf springs when in this position being designed 25 to support the rear covers of a sidewise opening book.
9. In a device of the type described, a rod for overlying the center of an opened sidewise opening book, angle members carried by the rod for engaging with the top and bottom edges of the book, a line indicator slideable on the rod and including a sleeve that extends transversely to the rod, and an indicating member slideable in the 30 sleeve, and adjustable to the right or to the left so as to accommodate itself to books of different widths.
10. In a device of the type described, a fixed member, a movable member, a rod carried by 35 the movable member, a line indicator slideable on the rod, and a cord extending from the line indicator and being secured to the fixed member.
11. In combination a fixed member, a movable member, a rod carried by the movable member, a line indicator slideable on the rod, a cord having 40 one end secured to the fixed member and means carried by the line indicator for adjustably securing the other end of the cord to the indicator whereby the indicator will be held in a fixed position with respect to the fixed member when the movable member is raised.
12. The combination with a copy holder having a fixed member and a movable member, of an attachment pivotally secured to the movable member, and having a sidewise opening book supporting portion, and spacing means 45 slideable along the attachment for swinging the attachment into the desired angular position with respect to the movable member.
13. An attachment comprising two hook-shaped arms, means supported by said arms for carrying a sidewise opening book, sleeves slideable on said arms, a cross bar interconnecting the sleeves, and spacing members carried by the sleeves.
14. In combination a fixed member, a movable 15 member, a rod carried by the movable member, a line indicator slideable on the rod, a spring clamp carried by the line indicator, a cord receivable in the clamp, means for tightening the clamp for securing the cord thereto, the other 20 end of the cord being attached to the fixed member.
15. In combination, a slotted bar having notches in its upper surface, a rod having a T-shaped head insertable through the slot, the under-surface of the T-shaped portion being inclined for providing teeth that can enter the notches, said notches and teeth being shaped for permitting sliding movement of the T-shaped head in one direction along the member and for 25 preventing movement in the oposite direction.
16. An article of manufacture comprising a slotted bar having notches in its upper surface, the notches being disposed on opposite sides of the slot, and each notch having a wall extending at right angles to the upper surface of the member, and a second wall extending at an angle with respect to the first wall.
17. An attachment for a copy holder comprising a pair of hook-shaped arms, a folding 40 shelf hinged to the arms, a member pivoted to the shelf and having slots therein, said shelf having a recess disposed adjacent to the member, a rod for holding a sidewise opening book in open position, said rod being receivable in any one 45 of the slots, and means for supporting the upper end of the rod, said recess receiving the rod when the book hinge is so thin that it necessitates the placing of the rod in one of the slots adjacent to the pivot point of the member.

BONNIE E. VAN ALSTYNE.
